HYDRAULIC PUMP

Roger F. Horton, Hempstead, N. Y., assignor, by
mesne assignments, to United Aircraft Corporation,
East Hartford, Conn., a corporation of
Delaware

Application November 15, 1945, Serial No. 628,942

20 Claims. (Cl. 103—4)

1
This invention relates to method and means for transforming or translating mechanical power into hydraulic power or vice versa in an efficient manner.

Accordingly, an object of the invention is to provide a simple, practical, and efficient device of the above mentioned kind.

Another object of the invention is to increase efficiency of hydraulic pumps and motors by providing means for forcibly exhausting fluid leakage which would otherwise collect within the casing and interfere with and obstruct free movement of parts moving within the casing.

A further object of the invention is to evacuate liquid leakage from within the casing of a rotary pump or motor and to utilize the space thus provided as an expansion chamber for the fluid employed in hydraulic circuits which are entirely air tight.

Another object of the invention is to provide an hydraulic pump or motor with an enclosed reservoir for the fluid employed in the device, which together with work output means, and suitable interconnecting conduit means, may provide an entirely enclosed hydraulic power circuit not subject to atmospheric pressure.

Another object of the invention is to provide an improved hydraulic pump or motor assembly which is compact, and the operation of which is not affected by changes in atmospheric pressure.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which,

Figure 1 is a schematic view showing an enclosed propulsion fluid reservoir and a work piece interconnected in an entirely enclosed circuit which is thus not subject to atmospheric pressure or changes thereof;

Figure 2 is a vertical section of a device embodying my invention;

Figure 3 is a horizontal section taken along the line 3—3 of Figure 2;

Figure 4 is a top plan view of the device partly cut away to show the reservoir;

2
Figure 5 is a perspective view on an enlarged scale of dish-like member 56; and

Figure 6 is a vertical cross section through said member.

In Figure 1 an hydraulic rotary pump A, such as is shown in detail in Figures 2—4, is shown connected with a work output means such for example as W, by fluid conduit means which is entirely enclosed thus providing a complete hydraulic circuit which is not affected by atmospheric pressure, or by changes in atmospheric pressure due to any cause, as for example to change of altitude or change in weather, or both. Since windshield wiper mechanism is illustrated as the work output means W a cross over valve V is included in the circuit.

The device shown herein in Figures 2—4, and which may be utilized either as a pump or a motor depending upon the direction of flow of the fluid employed, comprises a casing including a main body portion 10 and the combined cover and mounting standard or flange 11, which may be secured to the body portion by the cap screws 12.

Extending into the casing in alignment, from opposite sides, are the pintle 13 and the power shaft 14. Mounted within the casing for rotation on the pintle is the rotor 15, comprising a number of cylinders 16 in each of which is a piston 17 the outer end of which is adapted to abut against and is free to move on the inner race of a track ring assembly comprising the inner rotatable race 18 and the outer fixed race 19, the races being separated by the steel balls 20.

The track ring assembly is of less diameter than the interior of the casing and between the outer race 19 and the inner wall of the casing a spring member 21 (Figure 3) is interposed tending to urge the track ring into a position eccentric to the axis of the rotor. The position of the track ring is further controlled by means of the support clips 22 and 23. As illustrated herein support clip 22 is held in place by the screw 24 extending through the casing wall, the inner face of the screw being concave to provide a seat for the ball bearing 25 interposed between the screw 24 and the clip 22. The clip 23 is retained in place by the screw 26 which is provided with an inwardly opening bore 27 in which is received the plunger 28 projecting outwardly from clip 23.

The position of plunger 28 within bore 27 is determined by spring member 29 surrounding plunger 28 and having its extremities resting against the inner wall of the casing 10.

Extending through the casing wall intermediate

the screws 24 and 26, and disposed in triangular arrangement with spring 21 and positioning clip 22, is a coarse stroke adjusting screw 30, and extending radially through screw 30 is an adjusting screw 31 adapted for making fine adjustments.

Power shaft 14 is interconnected with rotor 15 in any suitable way as by pins 35 interconnecting semi-cylindrical bores 35^a provided in opposed relation in the circular flange 36 of the rotor and in the flange 37 positioned on the inner end of power shaft 14.

Pintle 13 is provided with the axially extending bores 40 and 41 adapted to communicate successively with the cylinders of the rotor assembly through the ports 40^a and 41^a respectively, which are spaced apart angularly around the pintle and connected by the surface slot 42^a. Interposed between the pintle 13 and the inner periphery of the rotor 15 is the force fitted bushing 42 having the ports 43^a adapted to register with the ports to the cylinders. Bore 40 is enlarged at its outer end, which is at the top of the device as shown, and this enlarged portion is provided with a thread 44 to receive a fluid conduit connection. The outer end of bore 41 communicates through port 45 with the fluid passage 46, which, as shown, extends into the casing at right angles to the pintle 13, and communicates through the perforated tubular wall member 47 with a reservoir 48 which it will be noted is entirely enclosed and thus not subject to atmospheric pressure. Access to reservoir 48 is had through the screw cap 49 having the inwardly projecting threaded shaft 50 adapted to engage in the casing boss 51 extending upwardly in the reservoir.

The partition means 47, which desirably may be of wire mesh, serves to permit a ready flow of propulsion fluid from the reservoir into the conduit 46 while preventing loss of energy due to turbulence and surging of the fluid within the reservoir and between conduit 46 and the reservoir. The outer end of conduit 46 may also be enlarged if desired and provided with a thread 52 to receive the end of a fluid conduit connection.

Positioned within the casing 10 under the rotor assembly a chamber or sump 54 is provided adapted to collect fluid leaking from the rotor assembly and to confine it in a closure from which it is exhausted as will be described. As illustrated herein the chamber is somewhat like a flattened bottle having a cylindrical body portion of substantial radius but narrow axially, with an upwardly opening mouth forming the port 53 which is adapted to receive fluid leaking from the rotor assembly. The bottom and the outer wall of the chamber 54 are defined by a portion 55 of the inner face of the casing cover 11. Chamber 54 is eccentric with respect to the median line of power shaft 14 as will be explained.

Positioned within the chamber 54 is a rotatable member 56 (Fig. 5) which in the embodiment of the invention shown herein by way of illustration is rotated by being fixed for rotation with power shaft 14, as by pin 58, in shaft 14 which pin engages slots 58^a in the central hub 62 of member 56. This member is dish-shaped having a concavity 60 in its upper surface, surrounding a central hub 62, to collect leakage fluid, and extending through the peripheral rim 63 of the member radially extending ports 64 are provided through which fluid is expelled under centrifugal force when the member is rotated, thereby setting up a rotary flow of the leakage fluid within

the chamber 54 around the periphery of member 56 and against the outer wall of the chamber.

In high pressure hydraulic pumps and motors generally leakage occurs, as for example between the pistons and the cylinder bores, and between the pintle and the surrounding bushing, and unless means are provided for preventing it this leakage accumulates in the casing and fills the space surrounding the rotor, and contact between the leakage fluid in the casing and the rotating rotor creates friction with resulting loss in efficiency. In the embodiment of the invention disclosed herein leakage occurs between the pistons and the cylinder bores 16 and also between bushing 42 and pintle 13. This leakage finds its way into the space below the rotor, and except for being exhausted as provided for herein would completely fill the casing and thus be in frictional contact with the rotor.

Leakage fluid collecting in concavity 60 is confined therein, and in chamber 54 after having been expelled from the concavity 60 through ports 64, by the annular baffle 66. Baffle 66 is bent up at both its inner and outer peripheries forming, an inner flange 68 which forms the port 53, and the outer flange 70 which has an outwardly projecting lip 72 fastened as by screw 74 to the upwardly projecting flange 76 of the casing.

The chamber 54 is designed to be eccentric with respect to the axis of rotatable member 56, which as illustrated herein is the axis of power shaft 14, in order that the space surrounding the periphery of member 56 will be non-uniform radially. Thus in the space around the periphery of member 56 a pressure will be built up, when member 56 rotates, which will be greatest at the greatest radial distance from the axis of rotation of member 56.

Interconnecting the low pressure side of the pump or motor and the interior of the said chamber 54 is a fluid passage 78, preferably having its mouth located at the greatest radial distance from the axis of rotation of the said member 56, whereby, due to the pressure built up within the chamber when member 56 is rotated, the leakage fluid is expelled from chamber 54 through the said passage 78 and is returned to the low pressure side of the pump or motor. It will now be understood that member 58 serves as a scavenger pump operating in a continuously evacuated pumping chamber, and cooperating with fluid passage 78 to return leakage fluid from the interior of the casing to the low pressure side of the pump or motor, with the result that the interior of the casing, and particularly the space around the rotor is kept free of leakage fluid.

It will be noted that during filling of the reservoir with fluid via the bore 50 any fluid which can pass through passage 78 will not completely or even substantially fill the expansion chamber 54 since it is filled with air and would merely build up a slight pressure therein. During rotation of the pump the member 56 will tend to expel fluid into the reservoir 48 and continue its scavenging action whenever the expansion chamber fluid leakage level is above the lip of the wall 68. However, during the scavenging operation air in the expansion chamber 54 will mix with a certain amount of the leakage oil as the oil is agitated around the rotor and will be carried out of said chamber into the reservoir where the air tends to rise from the liquid oil to pressurize the reservoir. In a closed system such as this a pressure balance is set up at a normal operating temperature, i. e., the air pressure in

the expansion chamber will assume a certain pressure value commensurate with said temperature and the evacuation pressure capacity of the pumping element 56 as compared to the pressure in reservoir 48. Hence the normal rise in pressure due to temperature in reservoir 48 will be enhanced by the pumping action of the scavenger element 56 which as mentioned above will at times be pumping an air-oil mixture. Therefore, with a closed system as described, the pumping mechanism, for given power conditions, will operate at a given pressure regardless of outside pressure variations such as changes in altitude in an aircraft.

To facilitate flow of leakage fluid into the concavity 60 in member 56 the power shaft 14 may be made with a hollow bore 80 leading from its inner extremity just below the inner end of the pintle and communicating with concavity 60 through the lateral ports 82 in the annular wall of shaft 14 and the ports 62a in hub 62. Perforations 84 may also be provided through the baffle 66 to permit leakage fluid which has not entered port 53, or the open end of bore 80 in power shaft 14, to flow down into the concavity 60 of member 56.

Interposed between the upper surface of the hub 62 of member 56 and the under surface of the flange 37 of the power shaft 14 is a spring member 86 which serves to exert pressure on the 30 rotor assembly to keep its cylinders centered with relation to the track ring assembly.

Any suitable sealing means may be provided surrounding the power shaft 14. As illustrated herein this means includes a loose washer 88, the 35 force fitted washer 90 and the packing assembly 92.

By exhausting leakage fluid from within the casing not only is the efficiency of the device increased by eliminating the waste energy expended in friction between the rotor and leakage fluid in the space through which the rotor turns, but a more compact system is made possible in which all parts of the fluid circuit are air-sealed and the space within the casing is employed as an expansion chamber for the fluid. Thus the fluid within the sealed system may be exchanged in either direction through the fluid passage interconnecting the reservoir and the sump, and the space within the casing, which is kept substantially evacuated as has been described, will function as an air chamber to apply air pressure to the liquid in said reservoir and thereby increase its pressure head above that due to the liquid in said reservoir and maintain said pressure head irrespective of external atmospheric pressure.

It will thus be seen that there has been provided by this invention a method and apparatus, in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawings is to be interpreted as illustrative and not in a limiting sense.

What I claim is:

1. A power translating device comprising, in combination, a housing having liquid inlet and discharge passages therein, liquid displacement power conversion elements in said housing for transferring liquid from said inlet to said dis-

charge passage, said housing defining a reservoir therein communicating with said inlet passage, said housing defining a sump below said elements, a liquid return passage interconnecting said sump and said reservoir, and additional pumping elements in said housing for transferring liquid from said sump to said liquid return passage.

2. A power translating device comprising, in combination, a housing having liquid inlet and discharge passages therein, liquid displacement power conversion elements in said housing for transferring liquid from said inlet to said discharge passage, said housing defining a reservoir therein communicating with said inlet passage, said housing defining a sump below said elements, a liquid return passage interconnecting said sump and said reservoir, pumping elements in said housing for transferring liquid from said sump to said liquid return passage, and a common drive shaft extending into said housing and driving said liquid displacement power conversion elements and said pumping elements.

3. A power translating device comprising, in combination, a housing having liquid inlet and discharge passages therein, liquid displacement power conversion elements in said housing for transferring liquid from said inlet to said discharge passage, said housing defining a reservoir therein communicating with said inlet passage, said housing defining a sump below said elements, a liquid return passage interconnecting said sump and said reservoir, a centrifugal pumping element in said sump, said sump and said pumping element being circular and said pumping element being positioned eccentrically with respect to the axis of said sump, said liquid passage having a port located in the portion of the periphery of the sump which is at the greatest radial distance from the axis of said pumping element.

4. A power translating device comprising, in combination, a casing having a first chamber therein, a rotor in said chamber having a plurality of substantially radial cylinders therein and pistons projecting from the outer ends of said cylinders, a drive shaft extending into said casing and coupled to said rotor, bearings carrying said rotor, a rotating guide member in controlling engagement with the outer end of said pistons for determining the positions of said pistons in said cylinders, bearings for said guide member, the axis of rotation of said guide member being parallel to the axis of rotation of said rotor, said casing having liquid inlet and outlet passages communicating with said cylinders, and a liquid reservoir chamber communicating with said inlet passage, said casing also having a second chamber in the lower portion thereof, a liquid passage extending from the peripheral portion of said second chamber to said reservoir through which liquid may be exchanged between said reservoir and said second chamber, and a centrifugal pumping element mounted for rotation in said second chamber by which liquid in said second chamber may be transferred to said reservoir.

5. A power translating device comprising, in combination, a casing having a first chamber therein, a rotor in said chamber having a plurality of substantially radial cylinders therein and pistons projecting from the outer ends of said cylinders, a drive shaft extending into said casing and coupled to said rotor, bearings carrying said rotor, a rotating guide member in con-

trolling engagement with the outer end of said pistons for determining the positions of said pistons in said cylinders, bearings for said guide member, the axis of rotation of said guide member being parallel to the axis of rotation of said rotor, said casing also having liquid inlet and outlet passages communicating with said cylinders and a liquid reservoir chamber communicating with said inlet passage, said casing also having a second chamber in the lower portion thereof, a liquid return passage extending from the peripheral portion of said second chamber to said reservoir, and a centrifugal pumping element in said second chamber, said pumping element being disposed in the bottom of said second chamber and comprising a dish-like rotor having a bottom and a rim carrying radiating liquid passages therein, and means for connecting said pumping element to a source of power.

6. A power translating device comprising, in combination, a casing having a first chamber therein, a rotor in said chamber having a plurality of substantially radial cylinders therein and pistons projecting from the outer ends of said cylinders, a drive shaft extending into said casing and coupled to said rotor, bearings carrying said rotor, a rotating guide member in controlling engagement with the outer end of said pistons for determining the positions of said pistons in said cylinders, bearings for said guide member, said casing also having liquid inlet and outlet passages communicating with said cylinders and a liquid reservoir chamber communicating with said inlet passage, said casing also having a second chamber in the lower portion thereof, a liquid passage extending from the peripheral portion of said second chamber to said reservoir, and a centrifugal pumping element disposed in the bottom of said second chamber and comprising a dish-like rotor having a bottom wall and a rim carrying radiating liquid passages therein, said second chamber and pumping element being substantially circular and said pumping element being positioned eccentrically with respect to the axis of said second chamber, the entrance of said liquid return passage being located in the portion of the periphery of the second chamber which is at the greatest radial distance from the axis of said pumping element.

7. A power translating device comprising, in combination, a casing having a first chamber therein, a rotor in said chamber having a plurality of substantially radial cylinders therein and pistons projecting from the outer ends of said cylinders, a drive shaft extending into said casing and coupled to said rotor, bearings carrying said rotor, a rotating guide member in controlling engagement with the outer end of said pistons for determining the positions of said pistons in said cylinders, bearings for said guide member, said casing also having liquid inlet and outlet passages communicating with said cylinders and a liquid reservoir chamber communicating with said inlet passage, said casing also having a second chamber in the lower portion thereof surrounding the axis of said shaft, a liquid return passage extending from the peripheral portion of said second chamber to said reservoir, and a centrifugal pumping element rotatable about the axis of said shaft and coupled to said shaft for rotation thereby, said pumping element being disposed in the bottom of said second chamber, and said pumping element comprising a dish-like rotor having a bottom wall and a rim carrying radiating liquid passages

therein, and leakage liquid guide walls in said casing for conveying leakage liquid into said dish-like rotor.

8. A power translating device comprising, in combination, a casing having a first chamber therein, a pintle extending downwardly into said chamber and having liquid inlet and outlet passages therein and terminating in ports on opposite sides of said pintle, a rotor in said chamber having a plurality of substantially radial cylinders therein and pistons projecting from the outer ends of said cylinders, said pintle comprising a bearing upon which said rotor is mounted for rotation about a vertical axis with the inner ends of said cylinders passing over said ports during rotation of said rotor, a rotating guide ring in controlling engagement with the outer ends of said pistons for moving said pistons inwardly in said cylinders during a portion of their rotational cycle, bearings pivoting said guide ring for rotation about an axis parallel to said axis of rotation of said rotor, a vertical drive shaft extending into said casing from the bottom thereof along the axis of said rotor, said shaft being coupled to said rotor, and a liquid reservoir chamber in said casing communicating with said inlet passage and located at a higher position in said casing than said ports.

9. A power translating device comprising, in combination, a casing having a first chamber therein, a pintle extending downwardly into said chamber and having liquid inlet and outlet passages therein and terminating in ports on opposite sides of said pintle, a rotor in said chamber having a plurality of substantially radial cylinders therein and pistons projecting from the outer ends of said cylinders, said pintle comprising a bearing upon which said rotor is mounted for rotation about a vertical axis with the inner ends of said cylinders passing over said ports during rotation of said rotor, a rotating guide ring in controlling engagement with the outer ends of said pistons for moving said pistons inwardly in said cylinders during a portion of their rotational cycle, bearings pivoting said guide ring for rotation about an axis parallel to said axis of rotation of said rotor, a vertical drive shaft extending into said casing from the bottom thereof along the axis of said rotor, said shaft being coupled to said rotor, and a liquid reservoir chamber in said casing communicating with said inlet passage and located at a higher position in said casing than said ports, said casing also having a second chamber in the lower portion thereof surrounding the axis of said shaft, a liquid return passage extending from the peripheral portion of said second chamber to said reservoir, and a centrifugal pumping element rotatable about the axis of said shaft and coupled to said shaft for rotation thereby, said pumping element being disposed in said second chamber.

10. A power translating device comprising, in combination, a casing having a first chamber therein, a pintle extending downwardly into said chamber and having liquid inlet and outlet passages therein and terminating in ports on opposite sides of said pintle, a rotor in said chamber having a plurality of substantially radial cylinders therein and pistons projecting from the outer ends of said cylinders, said pintle comprising a bearing upon which said rotor is mounted for rotation about a vertical axis with the inner ends of said cylinders passing over said ports during rotation of said rotor, a rotating guide

ring in controlling engagement with the outer ends of said pistons for moving said pistons inwardly in said cylinders during a portion of their rotational cycle, bearings pivoting said guide ring for rotation about an axis parallel and eccentric to said axis of rotation of said rotor, a vertical drive shaft extending into said casing from the bottom thereof along the axis of said rotor, said shaft being coupled to said rotor, and a liquid reservoir chamber in said casing communicating with said inlet passage and located at a higher position in said casing than said ports, said casing also having a second chamber in the lower portion thereof surrounding the axis of said shaft, a liquid return passage extending from the peripheral portion of said second chamber to said reservoir, and a centrifugal pumping element rotatable about the axis of said shaft and coupled to said shaft for rotation thereby, said pumping element being disposed in the bottom of said second chamber and said pumping element comprising a dish-like rotor having a bottom wall and a rim carrying radiating liquid passages therein.

11. A power translating device comprising, in combination, a casing having a first chamber therein, a pintle extending downwardly into said chamber and having liquid inlet and outlet passages therein and terminating in ports on opposite sides of said pintle, a rotor in said chamber having a plurality of substantially radial cylinders therein and pistons projecting from the outer ends of said cylinders, said pintle comprising a bearing upon which said rotor is mounted for rotation about a vertical axis with the inner ends of said cylinders passing over said ports during rotation of said rotor, a rotating guide ring in controlling engagement with the outer ends of said pistons for moving said pistons inwardly in said cylinders during a portion of their rotational cycle, bearings pivoting said guide ring for rotation about an axis parallel and eccentric to said axis of rotation of said rotor, a vertical drive shaft extending into said casing from the bottom thereof along the axis of said rotor, said shaft being coupled to said rotor, and a liquid reservoir chamber in said casing communicating with said inlet passage and located at a higher position in said casing than said ports, said casing also having a second chamber in the lower portion thereof surrounding the axis of said shaft, a liquid return passage extending from the peripheral portion of said second chamber to said reservoir, and a centrifugal pumping element rotatable about the axis of said shaft and coupled to said shaft for rotation thereby, said pumping element being disposed in said second chamber and said pumping element comprising a dish-like rotor having a bottom wall and a rim carrying radiating liquid passages therein, and leakage liquid guide walls in said casing for conveying leakage liquid into said dish-like rotor.

12. In an hydraulic power translating device comprising, a casing, a pintle extending into said casing and having liquid inlet and discharge passages therein terminating in ports on the opposite sides of said pintle, a rotor having a plurality of radial cylinders therein and pistons projecting from the outer end of said cylinders, said pintle comprising a bearing upon which said rotor is mounted for rotation around the pintle with the inner ends of said cylinders passing over said ports during rotation of said rotor, a track ring rotatably mounted intermediate the

pintle and the casing in controlling engagement with the outer ends of said pistons for moving said pistons inwardly in said cylinders respectively during a portion of their rotational cycle, 5 and means for controlling the position of the axis of rotation of the track ring with respect to the axis of rotation of the rotor comprising, a ball contact and means supporting it within the casing in position to engage the exterior of said track ring, an adjustable positioning screw extending through the casing and adapted to contact the exterior of said track ring, and resilient means supported in the casing and pressing against the exterior of the track ring and urging it against the said ball contact and said positioning screw.

13. A liquid-mechanical power converter comprising, in combination, a casing having a chamber therein and liquid inlet and outlet passages 20 entering said chamber, hydraulic-mechanical power conversion members for transferring liquid from said inlet to said outlet passage, a power transmitting shaft coupled to said power conversion members and extending through said casing wall, a reservoir communicating with one of said passages, liquid conduits connecting said outlet and inlet passages outside said converter, a liquid passage interconnecting said reservoir and the lower part of said chamber which is thus able to serve as an expansion chamber for the liquid of the system and to apply air pressure to the liquid in said reservoir and thereby increase its pressure head above that due to the liquid in said reservoir and maintain said pressure head irrespective of external atmospheric pressure, and means for exhausting liquid from the lower part of said chamber and for returning it through said liquid passage to said reservoir.

14. A radial pump comprising, in combination, a casing having a chamber therein, a pintle extending into said chamber and having liquid inlet and outlet passages therein and terminating in ports on opposite sides of said pintle, a rotor in said chamber mounted to rotate on said pintle, said rotor having a plurality of radial cylinders therein and pistons projecting from the outer ends of said cylinders, the inner ends of said cylinders being positioned to pass over said ports during rotation of said rotor, a rotating guide member in controlling engagement with the outer ends of said pistons for moving said pistons inwardly in said cylinders during a portion of their rotational cycle, bearings pivoting said guide member for rotation on an axis parallel to but offset from the axis of rotation of said rotor, a drive shaft extending through the wall of said casing and coupled to said rotor, a liquid reservoir communicating with said inlet passage, liquid conduits connecting said liquid outlet and inlet passages outside said pump, said casing and said conduits and reservoir together defining a sealed system, said casing having a liquid return passage extending from the lower part of said chamber to said reservoir, and a liquid pump in the lower part of said chamber operatively positioned with respect to said liquid return passage for returning leakage liquid from said chamber to said reservoir.

15. A power translating device comprising in combination, a housing, a plurality of liquid passages extending through the wall of the housing, liquid displacement power conversion elements movably mounted in said housing for transferring liquid from one of said passages to the other, 70 said housing defining a reservoir, a port extend-

ing through the housing wall into communication with said reservoir, and a removable plug accessible from outside said housing and adapted to be seated in and to close said port, said reservoir being in communication with one of said liquid passages.

16. A power translating device comprising in combination, a housing having liquid inlet and discharge passages therein, said housing defining a chamber having liquid displacement power conversion elements movably mounted therein for transferring liquid from said inlet to said discharge passage, a reservoir, in communication with one of said liquid passages, and a liquid conduit separate from said one passage interconnecting said reservoir and the interior of said chamber, and movable pumping elements in said chamber adapted to transfer liquid from said chamber to said reservoir through said liquid conduit.

17. A power translating device comprising in combination, a housing having liquid inlet and discharge passages therein, liquid displacement power conversion elements movably mounted in said housing for transferring liquid from said inlet to said discharge passage, and a reservoir in communication with one of said passages, said housing also defining a chamber beneath said power conversion elements, a fluid passage interconnecting said chamber and said reservoir through which fluid expanded in said reservoir may be discharged into said housing, and a movable pumping element in said chamber adapted to transfer to the reservoir fluid accumulating in said chamber.

18. A power translating device comprising in combination, a casing, a rotor in said casing having a plurality of substantially radial cylinders therein and pistons projecting from the outer ends of said cylinders, said casing having liquid inlet and outlet passages communicating with said cylinders, a drive shaft extending into said casing and coupled to said rotor, bearings carrying said rotor, a rotating guide member in controlling engagement with the outer end of said pistons for determining the position of said pistons in said cylinders, a liquid reservoir communicating with said inlet passage, a scavenger pumping means having its inlet in communication with liquid collecting in said casing, a liquid passage extending from adjacent the bottom of the casing to said reservoir by which liquid accumulating within the casing may be transferred to said reservoir, and means connecting said scavenger pumping means to a source of power.

19. A power translating device comprising in combination a casing, a rotor in said casing having a plurality of substantially radial cylinders therein and pistons projecting from the outer ends of said cylinders, said casing having liquid inlet and outlet passages communicating with said cylinders, a drive shaft extending into said

casing and coupled to said rotor, bearings carrying said rotor, a rotating guide member in controlling engagement with the outer end of said pistons for determining the position of said pistons in said cylinders, a liquid reservoir communicating with said inlet passage, a chamber located below said sump and a passage communicating between said sump and said chamber, a centrifugal pumping element rotatably mounted in said chamber, means for interconnecting said pumping element to a source of power, and a liquid passage extending from the peripheral portion of said pumping chamber to said reservoir through which liquid may be exchanged between said reservoir and said pumping chamber.

20. A power translating device comprising in combination a casing, a rotor in said casing having a plurality of substantially radial cylinders therein and pistons projecting from the outer ends of said cylinders, liquid inlet and outlet passages communicating with said cylinders through said casing, a drive shaft extending into said casing and coupled to said rotor, bearings carrying said rotor, a rotating guide member in controlling engagement with the outer end of said pistons for determining the position of said pistons in said cylinders, a liquid reservoir communicating with said inlet passage, a liquid passage extending from the interior of said casing below said rotor to said reservoir, and means for exhausting liquid from said casing to said reservoir through said liquid passage, said liquid passage being adapted also to transfer liquid from the reservoir to the interior of the casing to utilize said space as an expansion chamber for said reservoir.
